CLAIM

The ornamental design for a construction components container with lid, as shown and described.

DESCRIPTION

FIG. 1 is a perspective view of the construction components container with lid.

FIG. 2 is a top plan view thereof.

FIG. 3 is a bottom plan view thereof.

FIG. 4 is a front elevational plan view thereof.

FIG. 5 is a rear elevational view thereof.

FIG. 6 is a right side elevational view thereof.

FIG. 7 is a left side elevational view thereof; and,

FIG. 8 is an exploded perspective view thereof.
